UNITED STATES PATENT OFFICE.

ROBERT WILLIAM KING, OF TORONTO, CANADA.

TEMPERATURE-REGULATOR.

SPECIFICATION forming part of Letters Patent No. 589,603, dated September 7, 1897.

Application filed December 4, 1895. Serial No. 571,056. (No model.)

To all whom it may concern:

Be it known that I, ROBERT WILLIAM KING, manufacturer, of the city of Toronto, in the county of York, in the Province of Ontario, Canada, have invented a certain new and useful Improvement in Temperature-Regulators, of which the following is a specification.

My invention relates to improvements in ventilating apparatus more particularly adapted for greenhouses where automatic means are used in connection with the shutters or dampers to operate the same when a slight change in temperature occurs, so they will open and close gradually and positively, and, further, in applying such means when at rest to effectually hold the shutters closed during windy or stormy weather; and it also consists of the details of construction, as will be hereinafter described, and particularly pointed out in the claims.

The invention is illustrated in the accompanying drawings, in which—

Figure 1 is a perspective view, partially in section, of my improved operating mechanism for the shutters, showing the shutters and operating mechanism half raised. Fig. 2 is a view showing a vertical section of the valve and the normal position of the lever and valve as it would appear when the mechanism is in a half-raised position. Fig. 3 is a similar view showing the position of the double-acting valve and lever during an increase of temperature. Fig. 4 is a similar view showing the position of the double-acting valve and lever when the increase of temperature has stopped. Fig. 5 is a similar view of the double-acting valve and lever during a decrease of temperature. Fig. 6 is a similar view showing the position of the double-acting valve and lever when the decrease of temperature has stopped.

In the drawings like letters of reference indicate corresponding parts in each figure.

A is a tubular standard which extends from top to bottom of the greenhouse, being securely fastened to the floor and roof.

B is a bracket which is secured to the tubular standard and is provided with an outwardly-extending arm B'.

C is a thermostat which is comprised of the arm B' with the outside metal plate c and in-

side metal plates c' and the inner rubber plate c² and outer rubber plate c³. The plates are made substantially triangular in form. 55

D and D' are hangers suitably riveted to the metal plates c and c'. The hangers D and D' have a pin d extending through their lower ends, which are separated and twisted at right angles to the plane of the metal plates 60 c and c', so that the pin d is in a parallel plane to such plates.

E is a bent lever having a forked end e, which straddles the pin d. The lever E is pivoted at e' on the link F, which is secured 65 at its lower end to the turning spindle f of the valve F'.

G is the valve-box, which is provided with the upper port g, side port g', and the lower port g². 70

The valve F' is provided with the two ports f' and f², communicating with the central port f³ and the concentric discharge-port f⁴, which is designed to connect the two ports g and g' or the two ports g' and g². 75

H is a cylinder, the heads H' and H² of which are formed with bracket-shaped extensions h' and h², by means of which and straps h³ and h⁴ the cylinder is secured to and supported upon the tubular standard A. The cylinder H is a double-acting one and is provided with a piston I, having a rod I', which extends through the head H', provided with a suitable bushing. The head has a saucer-shaped recess h at the top, as shown. It is intended 85 that the cylinder should be operated by hydraulic pressure and controlled through the valve F', and for this purpose I provide a supply-pipe J, provided with a faucet j, which pipe leads to the central port f³ of the valve F'. The port g' in the valve-box G has a downwardly-extending pipe K leading to the saucer-shaped recess h on the top of the head H'. The port g² is connected by a pipe L to the interior of the cylinder through the head 95 H', and the valve-box G is supported by a plate L' upon the pipe L. The valve F is held in position by a set-screw l, extending through the upturned end of the plate L'. The port g is connected by a pipe M through the head H² to the interior of the cylinder. 100

N is a drip-pipe extending downwardly from the saucer-shaped recess in the head.

O is a relief-tap secured in the head H² and

communicating with the interior of the cylinder. The tap O is generally kept closed.

P is a lever pivoted upon the hanger p, secured to the bottom of the head H'. The lever P is connected by a rod p' to the bent lever E and by a rod p² to an arm q, secured to the common operating-shaft Q of the shutters, and is preferably provided with a weight p³ to provide for quick action of such lever.

10 The shaft Q is journaled in suitable hanger-bearings R, extending downwardly from and suitably secured to the roof S.

15 Take the shutters, and U the arms, which are suitably secured to the shaft Q. Each arm is preferably provided with an end ring u, swiveled to the tubular end bracket u'. Through the ring u extends the connecting-rod t, which is hinged at the top to the bracket t', secured to the bottom of the sash of the shutters.

20 The rod t has preferably formed on it an enlargement t² and extends through the ring u, this enlargement being on the ring u and serving to lift the rod t when said arm U is raised. The enlargement t² is designed to 25 form a stop against which the lever abuts to lift the shutters without any intervention of a spring. The enlargement t² also serves to receive a pressure from the spring u² of any desired tension to hold the shutter steady and 30 prevent its vibration or movement due to the wind.

35 u² is a spiral spring extending between the ring u and the split pin u³, extending through the bottom end of the rod t.

40 V is an arm secured to the shaft Q and connected by a rod v to the pin v' on the sleeve v², located on the piston-rod I'. The piston-rod I' at its upper end extends through a supporting-bracket W, secured to the tubular standard A. The sleeve v² has an outwardly-extending bracing-arm v³ attached to or forming part of the same, which has a forked end extending partially around the tubular standard.

45 Having now described the principal parts involved in my invention, I shall briefly describe the operation of the apparatus.

50 As hereinbefore premised, the piston in the cylinder is shown half raised, so as to half raise the shutter. This is the normal position in which the apparatus is set for the desired temperature of the greenhouse. The normal position of the valve is shown in Fig. 2. Upon an increase of temperature the plates of the thermostat will expand, and as the rubber plates expand more rapidly than the metal plates it will be seen that the tendency of the elongation of the rubber plates will be to cause the metal plates to curl up at their lower 55 end, and thereby bring the hangers D and D' 60 with the pin d in the direction indicated by arrow. This movement of the pin d will cause the lever to move laterally in the direction indicated by arrow, as shown in Fig. 3, thereby turning the valve and bringing the port f' opposite the port g. The water will 65 now pass through the pipe J, ports f³, f', and

g, and by the pipe M through the bottom head of the cylinder, and thereby raise the piston and swing the arms U upwardly, so as to further raise the shutter or set of shutters T. Immediately after this action takes place the lever q, being also raised at the same time, will draw upon the rod p² and the rod p', so that the lever E will be tilted on the pin d, acting 75 as a fulcrum, and will thus restore the valve F' to its normal position. A repeated action like this will continually take place until the shutter is raised to its full limit or until temperature ceases to rise to normal. Should, however, the temperature decrease, the rubber plates c² and c³, contracting more quickly than the metal plates c and c', will cause the hangers D D' to move in the opposite direction and bring the pin d in the opposite direction, as indicated in Fig. 5, and thereby throw the lever E laterally in the same direction, so as to throw the port f² opposite the port g². The water now entering through the pipe J will pass through the ports f³ f² g² and pipe 90 L into the top of the cylinder, and thereby force the piston downwardly, so as to close the shutters. Immediately, however, after the port is thrown into the position above described the rod p² will act upon the lever P 95 and rod p', so as to pull down the lever into the position shown in Fig. 6, thereby throwing the ports of the valve closed again. This action will be repeated until the temperature ceases to fall or the shutters are closed.

100 In Fig. 3 it will be noticed that the port f' connects the ports g' and g², so that when the water is flowing in at the bottom of the cylinder it may flow out from above the piston through the pipes L, ports g² f⁴ g', and pipe K into the saucer-shaped top of the head and pass downwardly through the drip-pipe N.

110 In Fig. 5 it will be noticed that when the water is causing the piston I to move downwardly the ports g and g' will be connected by the port f⁴, and consequently the water below the piston will be caused to ascend through the pipe M, ports g, f⁴, and g', and out through the pipe K, as hereinbefore described.

115 No matter which way the apparatus may be acting, whether to reduce the temperature by opening the shutters or to increase it by shutting the shutters in order to bring it to normal temperature, such apparatus, being 120 double-acting, will serve as a positive means for forcing the shutters toward the open as well as toward the closed positions.

125 Should a wind-storm occur and the temperature be suddenly reduced, my apparatus will act very rapidly to close the shutters and hold them closed.

130 If in cold weather icicles should form in some of the shutters of the set, it will be seen from the spring V' being between the ring of the arm U and the end of the connecting-rod t that such spring will give and allow the shutters where the obstacles prevent their closing to only partially close without pre-

venting the effectual closing of the remaining shutters of the set. When the icicles are being caused to melt from the temperature in the house, it will be seen that as the 5 springs are exerting a constant tension on such shutters they will gradually draw them to their seats until they are entirely closed. It will also be understood that a fine adjustment of each shutter of the set in relation to 10 the remaining shutters is not required, as the spring will compensate for any slight difference in position, so that when the apparatus is operated all the shutters will be effectually and completely closed.

15 Although I describe the spring operating with the actuating-arms of the shutters in the apparatus hereinbefore mentioned, it will be understood that the same or an equivalent device might be employed if the apparatus was actuated by hand instead of by hydraulic pressure.

Again, in large buildings it will be understood that the thermostat may be placed in any suitable position in the building and the 20 actuating-valve and operating-cylinder at any desired distance apart without departing from the essential features of my invention.

25 What I claim as my invention is—

1. In combination, in a ventilating apparatus for greenhouses, the shutters, means for automatically actuating the same comprising the thermostat, the pin carried thereby, the cylinder, having a piston, said piston being in connection with said shutters, the water-supply for said piston, the valve for controlling said supply, the lever fulcrumed on said pin, the connections between said lever and the shutters and the link interposed between said lever and said valve for controlling the 35 same, substantially as described.

2. In a ventilating apparatus, the combination with a thermostat, down-hangers therefrom connected by a pin, a double-acting valve provided with a suitable supply-pipe, a double-headed cylinder and piston, the rock-shaft operated therethrough and pipes connecting the ports of the valve to the interior of the cylinder through each end, a bent lever having a forked end straddling the pin 45 extending between the down-hangers, a link secured on the end of the double-acting valve and having its upper end forming a pivot for the bent lever and the rod p' , lever P , rod p^2 , arm q and rock-shaft Q all actuated as and 50 for the purpose specified.

3. In a ventilating apparatus, the combination with the thermostat and the pin d deriving a lateral movement therefrom, of the valve F' provided with the ports $f' f^2 f^3$ and

f^4 and the valve-box provided with the ports g , g' and g^2 , the supply-pipe for the port f^3 , the drip-pipe for the port g' and the double-headed cylinder provided with a piston and rod, the ventilator operated thereby, a pipe connecting the port g^2 to the upper end of 60 the cylinder and a pipe connecting the port g to the bottom of the cylinder and means for controlling the relation of the port f' to the port g and the port f^3 to the ports g' and g^2 simultaneously and for controlling the position of the port f^3 to the port g^2 and the port f^3 to the ports g and g' simultaneously as and for the purpose specified.

4. In a ventilating apparatus, the combination with the thermostat and the pin d deriving a lateral movement therefrom, of the valve F' provided with the ports $f' f^2 f^3$ and f^4 and the valve-box provided with the ports g , g' and g^2 , the supply-pipe for the port f^3 , the drip-pipe for the port g' and the double-headed cylinder provided with a piston and rod, the rock-shaft operated thereby, the shutters operated through said shaft, a pipe connecting the port g^2 to the upper end of 70 the cylinder and a pipe connecting the port g to the bottom of the cylinder and a lever E fulcrumed on the pin d connected by a link F to the valve F' and operated from the rock-shaft Q as and for the purpose specified.

5. The combination of a shutter, a rock-shaft suitably supported, an arm rigidly secured at one end to the rock-shaft and reaching toward the shutter and provided at its other end with a perforation, a rod attached at one end to the shutter and extending 80 through the perforation in the arm, a stop arranged on the rod above the arm, a stop on the rod beneath the arm, a spring on the rod resting at one end against the lower stop and at the other against the arm, and means for 85 rocking the shaft, substantially as described.

6. The combination of a shutter, a rock-shaft suitably supported, an arm rigidly secured at one end to the rock-shaft, and reaching toward the shutter and provided at the 90 other end with a swiveled guide, a rod attached at one end to the shutter and extending through the guide on the arm, a spring on the rod, a stop on the rod designed to abut against the guide, a stop to limit the movement of the opposite end of the spring and means for rocking the shaft, substantially as 95 described.

ROBERT WILLIAM KING.
